SHOE HEEL AND METHOD OF MAKING
SAME

Albert F. Bancroft, West Newton, Mass., assignor
to Bancroft-Walker Company, Waltham,
Mass., a corporation of Massachusetts

Application March 27, 1937, Serial No. 133,337

6 Claims. (Cl. 12—147)

This invention pertains to improvements in shoe heels and to a method of making the same, and relates more particularly to the manufacture of that type of heel in which a wooden core has its 5 sides and breast surface covered with sheet material.

Heels having wooden cores are usually covered by the shoe manufacturer as a step in the shoe-making apparatus in order that the covering may 10 conform in respect to material appearance, etc., to the other elements of the shoe in which the heel is to become a part. Usually the outer surface (that is to say, the curved rear and lateral edges) of the heel is covered (before the heel is 15 attached to the shoe bottom) with thin leather or fabric matching that used in the shoe upper, although other and contrasting materials are sometimes used, for example, thin celluloid. In a Cuban type heel the breast surface is also 20 covered (before the heel is attached) with thin sheet material, commonly like that employed in covering the outer heel surface. On the other hand, the breast surface of a Louis heel is usually 25 left uncovered until after the heel has been secured to the shoe bottom, and is then covered with a thin, skived-up flap integral with the outer sole. In either case the cover for the breast 30 surface of the heel is a separate part independent from the covering of the outer heel surface, and in either case difficulty has been experienced in 35 imparting to the forward corners of the heel that neat, sharply angular appearance desired by the manufacturer of high grade shoes. Usual methods of covering the heel tend either to produce a bulge or ridge adjacent the corner and/or to 40 form a round rather than a sharply angular corner, or alternatively to provide so insecure a union of the outer and breast coverings at the corners as to invite separation of the covering members at these points, with consequent gaping and exposure of the core,—commonly followed by fraying of the raw edges and a resultant 45 unsightly appearance.

While it has heretofore been proposed to trim 45 off the outer covering flush with the breast surface and then to lap the breast covering over the exposed front edges of the outer covering, this requires very careful work on the part of the operator, and even when properly done, the breast 50 covering tends readily to separate from the outer covering at the corners. On the other hand, if the margin of the outer covering is turned inwardly over the breast so as to underlap a substantial area of the breast covering material, 55 a rounded corner results which, as above noted,

is undesirable from the standpoint of fine shoemaking. While suggestions have been made for skiving or beveling the edge of the outer covering and/or the margins of the breast covering material, or for turning the edges of the outer or breast covering members inwardly into deep narrow slots cut in the core, such suggestions are not practical from the standpoint of factory production, since they involve expert, careful and unduly expensive operations. 10

The principal object of the present invention is to provide an improved wood heel and method of covering heels whereby it is possible, by factory methods and at a reasonable cost, to produce heels whose outer and breast surfaces are 15 neatly and effectively covered,—the corners being sharp and the breast being substantially free from unsightly ridges, although the breast covering overlaps portions of the outer covering to an extent sufficient to prevent unsightly gaping or 20 tendency to become loose and ragged at the corners during use. 25

A further object is to provide an improved method of covering heels applicable both to Cuban and Louis heels. 25

Further objects and advantages of the invention will be made manifest in the following more detailed description and by reference to the accompanying drawings, wherein

Fig. 1 is a side elevation of the core of a Louis heel; 30

Fig. 2 is a front elevation of the core of Fig. 1;

Fig. 3 is a section on the line 3—3 of Fig. 2;

Fig. 4 is a section similar to Fig. 3, but to larger scale, showing the outer covering applied to the 35 core;

Fig. 5 is a fragmentary perspective view of a shoe having a Louis heel and illustrating the step of covering the breast surface in accordance with the present invention; 40

Fig. 6 is a transverse section through the heel of Fig. 5 after the covering is complete;

Fig. 6a is a view similar to Fig. 6, but illustrating a slight modification;

Fig. 7 is a side elevation of the core of a Cuban 45 type heel;

Fig. 8 is a front elevation of the core of Fig. 7;

Fig. 9 is a section on the line 9—9 of Fig. 8;

Fig. 10 is a fragmentary perspective view showing a Cuban heel with its sides covered and ready 50 for application of the breast covering; and

Fig. 11 is a transverse section showing a heel such as that of Fig. 10 with the side and breast surfaces covered.

Referring to the drawings, the numeral 1 design- 55

nates a core for a Louis heel, such core usually being of wood but, so far as the present invention is concerned, being of any desired and suitable material. This core has the outer curved surface 5 2, including the rear and side portions of the heel, and the forward or breast surface 3. This breast surface, in the Louis type heel, extends upwardly and forwardly to form a substantially horizontal portion 3^a.

10 In accordance with the present invention, channels 4 and 5 (Fig. 3) are formed in the breast surface adjacent to the opposite margins of the breast. As illustrated in Fig. 3, these channels are preferably of substantially wedge-shape in transverse section, the narrow edge of the channel being substantially coincident with the forward corner of the core,—the rear wall 6 of the channel being inclined, and the thick edge 7 of the channel being substantially perpendicular to the main portion 15 of the breast surface. The width of the channel at its edge 7 preferably is substantially equal to the thickness of the sheet material which is to be used in covering the outer surface of the heel. The result of the formation of these channels is to provide a very sharp, acute corner at the point 8 of the core. In the Louis type heel, these channels 4 and 5 extend upwardly but preferably gradually decrease in depth until they merge at the points 4^a and 5^a, respectively, with 20 the forwardly directed breast surface 3^a of the heel. However, if preferred, they may extend to the forward edge of the breast surface.

Having prepared the core in this manner, the selected outer covering material 9 is applied to the 35 outer surface 2, usually being secured in place by means of an appropriate cement or other adhesive. This outer covering usually is in the form of sheet material such as thin leather, textile fabric or the like, and is drawn snugly about the outer surface of the heel and secured firmly in place. The margins 10 and 11 (Fig. 4) of this covering are then turned in so as to lie within the channels 4 and 5, respectively, the margins being securely cemented to the walls 6 and 7 of the channels. In thus turning in the margins about the 40 corner 8 of the heel core, a very sharp angle is produced, while the forward, exposed surfaces of the flaps or inturned margins 10 and 11 substantially merge with the surface 3 of the heel breast.

50 A Louis heel is usually attached to the heel seat surface of a shoe bottom in this condition, that is to say, with its breast surface uncovered. As here illustrated, the shoe to which the heel is to be attached comprises the upper 12 and the outer sole 13. Preparatory to applying the heel, the rear part of the outer sole is skived to produce the thin, breast covering flap 13^a. After the heel has been attached, this flap 13^a is turned up against the breast surface of the heel and is secured firmly in position by means of cement or other appropriate adhesive. This flap 13^a overlaps the inturned margins 10 and 11 of the outer covering material and is cemented to the forward surfaces of these flaps. Since the covering material 9 and the flap 13^a usually are of a relatively soft and absorbent material, it is possible to obtain a very firm bond between these overlapping elements, the overlap being of substantial extent. The edges of the flap 13 are now trimmed off to lie 65 flush with the outer surface of the heel, thus producing the effect illustrated in Fig. 6, wherein it will be noted that the forward corners 16 and 17 of the heel are very sharp and angular, giving the desired neat, clean-cut appearance, while the breast surface is smoothly curved and substan-

tially free from any appreciable ridges or deep hollows.

As a further refinement of this method of procedure, the edges of the covering flap 13^a may be skived, as illustrated at 14^b and 15^b (Fig. 6a) so as to secure an even sharper angle at the heel corners. However, this involves an additional step and further expense and may not be necessary under ordinary conditions.

10 Referring to Figs. 7 to 11, the invention is illustrated as embodied in a heel of the Cuban type. This heel comprises a core 1^x of wood or the like having the outer surface 2^x and the breast surface 3^x, the latter being substantially straight from top to bottom but usually being curved concave 15 in a rearward direction. This core is provided at the right and left margins of its breast surface 3^x with channels 4^x and 5^x (Fig. 9) of wedge-shape in cross section similar to the channels 4 and 5 above described. Preferably these channels 4^x 20 and 5^x extend from top to bottom of the heel.

25 The outer covering 9^x of any suitable flexible material is secured to the outer surface 2^x of this core with its forward margins 10^x and 11^x disposed within the channels 4^x and 5^x, respectively, and suitably cemented in place. In this case the breast covering member 13^y may be of the same material as the outer covering 9^x or of any other suitable thin material appropriate for the purpose. This covering member 13^y may initially be 30 trimmed to conform substantially exactly to the contour of the breast surface of the heel and is then applied to the breast surface by means of cement or other suitable adhesive so as to cover the entire breast surface, including the forward 35 surfaces of the margins 10^x and 11^x of the outer covering. The covering 13^y may be applied to the breast surface of the Cuban type heel before the heel is secured to the shoe bottom, since in this case the breast covering member 13^y is not a part 40 of the outer sole. The result of the above method of procedure is to produce a heel of Cuban type having a good and permanent joint between the outer and breast covering members, and with corners which are sharp and angular, and a breast 45 surface which is free from ridges or sharp depressions.

50 While certain desirable modes of procedure have been described together with the resulting products, it is to be understood that equivalent steps may be substituted for those herein specifically described, and that the order of steps may be varied and that the resulting products, such as fall within the terms of the appended claims, are to be regarded as within the scope 55 of the invention.

I claim:

1. A heel core having a curved outer surface which extends forwardly to the front corners of the core, said core having in its breast surface 60 two marginal channels each substantially wedge-shape in transverse cross section, the thin edge of each channel being substantially coincident with the corresponding forward corner of the heel core, the thicker edge of each channel being 65 substantially perpendicular to the main portion of the breast surface and of a depth substantially equaling the thickness of the material to be used in covering the outer surface of the heel.

2. A heel comprising a core, sheet material covering the outer surface of the core and sheet material covering the breast surface of the core, the breast surface of the core having two marginal channels each extending inwardly from the corresponding corner, the inner edge at least of 70

each channel being substantially as deep, measured rearwardly from the normal breast surface of the core, as the thickness of the material which covers the outer surface of the core, said outer covering material being turned in around the corners of the core and having its margins disposed within the respective channels, the breast covering material overlapping said in-turned margins and terminating substantially flush with the outer surface of the heel at the corners of the latter, and means permanently securing the covering material to the core.

3. A heel comprising a core, sheet material covering the outer surface of the core and sheet material covering the breast surface of the core, the breast surface having two marginal channels each of substantially wedge-shape in transverse section, the thin edge of each channel being substantially coincident with the corresponding forward corner of the heel core, the thicker edge of each channel being of a depth substantially equaling the thickness of the outer covering material,—the margins of the outer covering material being turned inwardly around the corners of the core and being disposed and secured within the respective channels, and breast covering material overlapping the inturned margins of the outer covering with the edges of the breast covering substantially flush with the outer surface of the heel adjacent to the corners thereof, and means permanently securing the breast covering in position.

4. A core for a Louis shoe heel having in its breast surface two marginal channels extending from the tread surface of the core upwardly but gradually vanishing in the upper, forwardly directed portion of the breast surface of the core, said channels being substantially wedge-shape in transverse section with the thinner edge of the channel substantially coincident with the corresponding forward corner of the core, the thicker edges of the channels, at their deepest portions, being of a depth substantially equaling the thickness of the material to be applied for covering the outer surface of the core.

5. That method of making heels which comprises as steps providing a heel core having a breast surface, forming in said breast surface marginal channels each substantially wedge-shape in transverse section, the thin edges of the channels being substantially coincident with the corresponding forward corners of the core, securing flexible covering material to the outer surface of the core, turning the forward margins of the covering material inwardly about the forward corners of the core, disposing and securing said margins in the respective channels, applying and securing a flexible breast covering material to the breast surface so as to overlap the inturned margins of said outer covering, and trimming the breast covering material so that its edges are substantially flush with the outer surface of the heel adjacent to the corners of the latter.

6. That method of making and covering a Louis heel which comprises as steps preparing a heel core having a breast surface of Louis shape, forming in said breast surface marginal channels each of substantially wedge-shape in transverse section, each channel extending upwardly from the tread surface of the core but gradually vanishing in the upwardly, forwardly directed portion of the breast surface, the thin edges of the channels being substantially coincident with the forward corners of the core, securing flexible covering material to the outer surface of the core, turning the margins of said covering material inwardly about the forward corners of the core and securing said margins in the respective channels, laying a breast covering flap, constituting an integral portion of an outer sole, against the breast surface of the core with the edges of said flap overlying the turned-in margins of the outer covering material, securing the breast covering flap in position, and trimming the edges of the flap substantially flush with the outer surface of the heel at the forward corners of the latter.

ALBERT F. BANCROFT. 45
